UNITED STATES PATENT OFFICE

LUCIAN BERNHARD, OF NEW YORK, N. Y., ASSIGNOR TO BELL TELEPHONE LABORATORIES, INCORPORATED, OF NEW YORK, N. Y., A CORPORATION OF NEW YORK

DESIGN FOR A DESK STAND FOR A HAND TELEPHONE

Application filed May 10, 1930. Serial No. 35,561. Term of patent 14 years.

To all whom it may concern:

Be it known that I, LUCIAN BERNHARD, a citizen of the Republic of Germany, residing at New York, in the county of New York and State of New York, have invented a new, original, and ornamental Design for a Desk Stand for a Hand Telephone, of which the following is a specification, reference being had to the accompanying drawing, forming a part thereof.

Fig. 1 is a front view; and

Fig. 2 is a plan view showing my new design of a desk stand for a hand telephone.

The rear of the desk stand is substantially the same as the front with the dial omitted.

I claim:

The ornamental design for a desk stand for a hand telephone, as shown and described.

In witness whereof, I hereunto subscribe my name this 5th day of May, 1930.

LUCIAN BERNHARD.
